UNITED STATES PATENT OFFICE.

FRANK L. O. WADSWORTH, OF SEWICKLEY, PENNSYLVANIA.

WATER-HEATER CONSTRUCTION.

1,248,958.

Specification of Letters Patent.

Patented Dec. 4, 1917.

Application filed October 3, 1911. Serial No. 652,577.

To all whom it may concern:

Be it known that I, FRANK L. O. WADSWORTH, a citizen of the United States, residing at Sewickley, in the county of Allegheny and State of Pennsylvania, have invented 5 certain new and useful Improvements in Water-Heater Constructions, of which the following is a specification.

The invention relates to improvements in what are known as instantaneous water heaters wherein the supply of gaseous fuel is controlled both by the thermostatic and water actuated mechanism, and has for its primary objects; the provision of a controlling mechanism including a single gas valve and single water actuated member wherein the water actuated member is controlled from the thermostat more positively than in apparatus of this general character 20 as heretofore constructed; the provision of an apparatus of the character specified wherein the operation of the water actuated member is controlled thermostatically by reversing the water pressure upon such water actuated member; and in general, the provision of a simplified and reliable mechanism for controlling the supply of fuel to the burners by the water pressure and by the temperature of the water in the heater. 25 Certain embodiments of the invention are 30 illustrated in the accompanying drawings, wherein:—

Figures 1 to 4 inclusive are diagrammatic views indicating in various forms the general principle of operation of the apparatus; Figs. 5 and 6 are front and side elevations respectively of a water heater equipped with one form of my controlling mechanism; Fig. 7 is a section through the form 40 of controlling mechanism shown in Figs. 5 and 6; Fig. 8 is a section through a modified form of controlling mechanism capable of use in place of the mechanism shown in Fig. 7; Fig. 9 is a section through another modified form of controlling mechanism; Fig. 10 is a section through another modified form of controlling mechanism; and Fig. 11 is a section through still another type of controlling mechanism.

Briefly stated the mechanism in all its various forms consists in a water actuated member, generally a piston or diaphragm, whose opposite sides are exposed to different pressures when the outlet from the heater 55 is opened, together with a thermostatically controlled means or valve so arranged that

when the temperature of the water rises above a predetermined point, the water pressure on the two sides of the water actuated member is reversed. The water actuated member is arranged so as to open the gas valve when the heater outlet is opened, and permit the closing of such valve when the thermostat controlling means causes a reversal of the water pressure on the water actuated member, and thus produces a reverse movement thereof.

The diagrams of Figs. 1 to 4 are intended to give a general idea of the principle of operation of my apparatus divorced from the detail mechanism in which the invention is preferably embodied, such detail mechanism being shown in Figs. 7 to 11. In the various diagrams A indicates the position of the parts of the apparatus when the temperature of the water is below a predetermined point and no water is being drawn from the heater, B indicates the position of the parts of the apparatus when the outlet from the heater is open, and C the position of the parts of the apparatus when the outlet is open and the temperature of the water rises above a predetermined point, at which time the thermostat causes a reversal of pressure on the water actuated member.

In the diagrammatic illustrations of Fig. 1, the cold water enters the apparatus at the opening 1 and is directed to one end or the other of the cylinder 2 by means of the water directing valve 3, the position of which is controlled by any suitable form of thermostat connected to the stem 4. In the cylinder 2 is located the water actuated member 5 which is connected to the stem 6 and by its movement serves to actuate the gas valve 7. The water passes away from the cylinder 2 through an opening 8 connected to the heating receptacle. A spring 9 serves to keep the water actuated member 5 in the normal left hand position shown in diagram A when no water is flowing. When water is turned on, it passes from the opening 1 through the right hand port in the thermostatically controlled valve 3, forces the piston 5 to the left, thus opening the gas valve 7, and passes on through the opening 8 to the heater. When the flow of water attains the desired temperature the thermostat moves the valve 3 to the position shown in diagram C, and the water now passes from the opening 1 through the left

hand port to the valve 3, forces the piston 5 to the right, thus closing the gas valve 7, and thus passes out through the opening 8 to the heater.

5 In the diagrammatic illustrations of Fig. 2, the thermostatically controlled valve 3² is placed on the outlet side of the cylinder 2', the water entering this cylinder through the opening 1', and moving the piston 5' 10 to the left—opening the gas valve—when the valve 3' is in the position shown in diagram B, and moving the said piston to the right—thus closing the gas valve—when the thermostat brings the valve 3' to the 15 position shown in diagram C. In this construction the piston is normally pressed to the right by the spring 9' and the valves 10 mounted on the rod 11 secured to the cylinder head controls the flow to the opposite sides of the piston, the direction of 20 flow being indicated by the arrows.

In the diagrammatic illustration of Fig. 3, the water actuated member is in the form of a diaphragm 5² which is moved up to 25 the position shown in diagram B when cold water is first turned on, the flow being from inlet 1² to the outlet 8² via ports 12 and 13 as indicated by the arrows, and is moved down to the position shown in diagram C 30 when the valve 3² has been shifted to the position shown in that diagram by the heating effect of the flowing water, the flow from the inlet to the outlet then being via the ports 14 and 15. As before, the movement of the water actuated member to the 35 position of diagram B opens the gas valve, and the movement of said diaphragm to the position shown in diagram C closes the gas valve.

40 In the diagrammatic illustration of Fig. 4, the water actuated member is operated by differential pressure, the chambers on the two sides of the diaphragm being connected to two points X and Y of different potential 45 in the flowing stream of water. In this case the thermostatically controlled valve 3³ operates, when in the position shown in diagram B, to connect the chamber on the lower side of the diaphragm 5³ with the point 50 Y of lower potential (via passages 16, 17 and 18), and the chamber on the upper side of the diaphragm with the point X of higher potential (via passages 19 and 20). This results in a depression of the 55 diaphragm and with it of the gas valve 7³, thus allowing fuel to flow to the main burners of the heater. When the water has been heated to a point at which the thermostat is set to act, the latter moves the 60 valve 3³ to the position shown in diagram C, and in this position the connections to the chambers on the two sides of the diaphragm are reversed, the point X being connected to the lower side of the diaphragm 65 via the passage 21 and the point Y being

connected to the upper side of the diaphragm via the passage 22, and the diaphragm is forced upward closing the gas valve 7³.

Referring to the general arrangement of parts as shown in Figs. 5 and 6, which figures illustrate the ordinary type of water heater with my improvement applied thereto; D is the casing of the heater; E, F and G are the upper coils; H is the lower reverse coil of the heater connected to the upper coils by means of the pipe I; K are the burners mounted upon the usual burner ring; L is the gas supply pipe; M is the casing of the valve for controlling the supply of gas to the burners; N is the pipe leading from the casing of the gas valve to the burner ring; O is the thermostat casing; and P is the casing containing the water actuated member, the casings O and P being 85 shown in enlarged cross section in Fig. 7.

Referring now to Fig. 7 in connection with Figs. 5 and 6, 31 is the cold water inlet by means of which water is supplied to the heater from the main, and this pipe communicates with the chamber 32 in which is located the thermostatically controlled water-flow valve 33 which corresponds in function to the valve 3 heretofore referred to in the diagrammatic apparatus of Fig. 1. 95 This valve 33 is provided with two heads 34 and 35 which are adapted to engage respectively with the seats 36 and 37. When the valve is in the position shown in the figure with the head 35 in engagement with the seat 37, the water flowing into the chamber 32 passes therefrom through the port 38 to the left hand end of the cylinder 39 containing the water actuated member 40. When the valve 33 is moved to the left so 105 that the head 34 engages with the seat 36, the water flowing into the chamber 32 passes through the port 41 to the right hand end of the cylinder 39. On the side of the cylinder opposite to the ports 38 and 41 there is provided an outlet port 42 so located that when the piston 40 is in its normal left hand position, the front edge of the port 42 is in communication with the right hand end of the cylinder 39. The port 42 opens into a 110 chamber which contains a spring supported and balanced ball check valve 43, that will permit the water to flow from the port 42 to the inlet 43^a of the upper coil E. (Fig. 5), but will prevent any flow of liquid in 115 the opposite direction. The water after passing through coils E, F, G, and H of the heater emerges at the outlet 44. The outlet 44 communicates with the lower end of a vertical thermostat chamber 45 and the 120 water emerging from the outlet 44 passes upward through this chamber and enters the pipe 46 which is connected to the house supply system. At the front end of the cylinder 39 there is a smaller cylinder 47, and 125 130

working in this cylinder is a plunger 48 which is provided at the left hand end with a head 49 engaging with the adjacent portion of the water actuated member 40. A pipe 50 leads from the middle of the thermostat chamber to a port communicating with the right hand end of the cylinder 47. A second port 55 leads from the left hand end of the cylinder 47 to the chamber back of the check valve 43. The water actuated member 40 is provided with a stem 51 which passes through a stuffing box 52 in the head of the cylinder 47, and is adapted to engage with the end of the stem 53 of the gas valve 54. The plunger 48 and the gas valve 54 are provided with compression springs numbered respectively 56 and 57, and the parts 40 and 48 are arranged so that when they have been moved by the spring 56 to the extreme left hand position—as determined by the engagement of the piston head of the plunger 48 with the shouldered end of the cylinder 47—the port opening 55 will be uncovered and water can pass from the thermostat chamber through the cylinder 47 and thence to the inlet 43^a of the heater coil. Located in the chamber 45 is a composite thermostat member of the usual construction comprising an outer expansible tube 58 of copper, brass, or zinc, and an inner negative element 59 of porcelain, nickel, steel or invar metal. The outer element 58 is secured at its upper end to the wall of the thermostat chamber, and is in abutting engagement at its lower end with the negative element 59. The latter terminates at its upper end in a knife edge 60 which contacts with the short arm of the multiplying lever 61. The long arm of this lever engages with an adjustable nut 62 on the end of the stem 63 which actuates the water flow valve 33. The lever 61 is kept in operative engagement with its operating parts by means of a tension spring 64, and the stem 63 is also provided with an adjustable washer 65 engaging a compression spring 66 surrounding the stem 63. The relative strengths of the springs 64 and 66 are about as two to one so that when the lever 61 is brought into engagement with the nut 62—by the expansion of the composite thermostat and the consequent retraction of the knife edge 60—the pull of the spring 64 will overcome the resistance of the compression spring 66 and move the valve over to the left until the head 34 engages with the seat 36 and closes the opening to the left hand end of the cylinder 39. When the lever 61 is moved to the right—by the contraction of the thermostat and the consequent lifting of the knife edge 60—until it is out of engagement with the nut 62, the spring 66 will move the valve 33 to the right to the position shown in the figure.

The operation of this mechanism is as follows: When no water is flowing through

the heater, and the parts are cold, the valve 33 will, as already stated, occupy the position indicated in the drawing. When a flow of water is started—as by opening the house tap connected with the pipe 46—water will be drawn away from the front of the piston 40 through the pipe 50 and the two ports 42 and 55 thus reducing the pressure on the right hand side of said piston and allowing it to be moved forward by the pressure of the water flowing in through the port 38. As the piston advances it carries with it the plunger 48 and closes off the opening to the port 55; but water will still continue to be drawn from in front of it through the port 42, and the piston 40 will continue to advance against the pressure of the springs 56 and 57 until it reaches the position indicated in dotted lines, or until the left hand side of the port 42 has been opened to allow the direct flow of water from the cold water supply pipe 31 through the port 38 to the house inlet 43^a. As the piston 40 advances, the end of its stem 51 engages with the end of the gas valve stem 53 and raises the gas valve 54 from its seat allowing the fuel to flow from the supply pipe L to the feed pipe N which leads to the main burners of the heater. The piston 40 will remain in its forward position as long as the valve 33 occupies the position shown in the figure and water continues to flow through the port 38. But when the temperature of the flowing liquid in the thermostat chamber 45 rises above a certain point the expansion of the positive element 58 and the consequent retraction of the knife edge 60 allows the thermostat lever 61 to be drawn into engagement with the nut 62 on the stem of the valve 33 and when this occurs the said valve will be moved to the left, closing the opening of the port 38 and opening that of the port 41. The flowing water will now pass from the cold water supply pipe to the front of the piston 40 and will force the latter back until the front edge of the port 42 is opened so that water can flow directly through that port to the inlet 43^a. The retraction of the piston 40 and with it the stem 51 allows the gas valve 54 to be closed by the pressure of its spring 57, thus shutting off the supply of fuel to the main burners. As the temperature in the thermostat chamber falls, the contraction of the positive element 58 will lift the knife edge 60 and move the lever 61 out of engagement with the nut 62, whereupon the valve 33 will be moved to the right by the spring 66, thus closing the opening to the port 41 and again opening that to the port 38. The pressure of the flowing water will then move the piston 40 again to its forward position, thereby once more opening the gas valve 54. These alternate opening and closing movements will continue with each corresponding fall and rise of the

temperature of the flowing liquid. When the flow of water is shut off, the pressure of the liquid on the two sides of the water actuated member 40 is at once equalized and the latter will normally be returned to its left hand position by the joint pressures of the springs 56 and 57. If, for any reason, any of the valve parts should stick and the spring pressures should be insufficient to overcome this sticking, the valve will be forced back to its normal left hand position by the continued heating of the water in the coils in the following manner: As soon as the flow of water stops, the ball check valve 43 will return to its seat and close off communication between the cold water inlet 43^a and the left hand end of the cylinder 39. The closing of the outlet in the house supply pipe 46 also confines the liquid on the outlet side of the heater, and the pressure generated in its confined body of liquid by the continued heating effect of the main burners will be communicated through the pipe 50 to the cylinder 47 and will act to force the plunger 48 and with it the member 40 back until the port opening 55 has been uncovered. Before this occurs, the gas valve 54 will have returned to its seat, thus cutting off the fuel supply to the main burners. The opening of the port 55 allows the water to circulate freely through the coils of the heater under the influence of the heat of the pilot light.

The uncovering of this port at each return of the water actuated member to its normal left hand position when the water is flowing also allows a small amount of cold water to flow from the port opening 42 through the port 55 and pipe 50 to the thermostat chamber 45, and this aids in more rapidly reducing the temperature in said chamber to the point where the thermostat will act to operate the water supply valve 33 and thereby again open the gas valve 54 in the manner previously described. This mixing of a small amount of cold water with the out-flowing hot water from the heater aids me in reducing or eliminating the ordinary lag of the thermostatic control mechanism and in securing a closer regulation of temperature by the control apparatus.

In the construction shown in Fig. 8, the control mechanism is all located in the out-flowing stream of water from the heater. The cold water enters the heater coil through a supply pipe 71, an ordinary spring check valve 72, and a water inlet connection 73 connected to the upper end of the heating coil or receptacle. After passing through this coil or receptacle, the water emerges from an outlet connection 74 which communicates with the lower end of the thermostat chamber 75. This thermostat chamber 75 contains a thermostat which, in this case, is

constructed of a nest of nickel steel or invar metal pipes, 76, 77, 78, screwed at their lower ends into a head 79 and brazed at their upper ends to a head 80 which carries a flexible diaphragm or corrugated member 81. The pipes 76, 77 and 78, the heads 79 and 80, and the corrugated box diaphragm 81 are filled with some liquid having a high coefficient of expansion such as petroleum oil, or paraffin, and the head 79 is provided with a tightly fitting screw 82 and a flexible washer and lock nut 83 by means of which the internal volume of the thermostat member may be varied. The corrugated diaphragm member 81 is capped by a plate 84 carrying a knife edge 84 which engages with a spring supported member 85; and this member 85 is provided with a screw 86 which engages in turn with the short arm of the thermostat lever 87. The parts last described are all inclosed in a rectangular box 88 communicating with the upper end of the thermostat chamber 75. The long arm of the thermostat lever 87 is pivotally connected to the center of the double headed supply valve 89 which is similar in construction to the corresponding valve 33 shown in Fig. 1. The two heads of this valve 89 are adapted to engage respectively with the valve seats 90 and 91 and thereby control the alternate flow of water through the ports 92 and 93. These ports lead to the upper and lower ends of a chamber 94 which contains the water actuated element 95. In this construction this element 95 is made in the form of a puppet valve engaging with the seats 96 and 96^a. The stem 97 is secured to the valve 95 and leads downward through an auxiliary chamber 98 and a stuffing box 99 to the gas valve stem 100. The stem 100 passes through the front wall of the gas valve chamber 101 and is secured to the gas valve 102. The latter is provided at its back with a boss carrying a leather washer 103 which, when the gas valve is open, is seated against the front wall of the gas valve chamber thereby preventing any leakage of gas around the stem 100 and eliminating the necessity for a stuffing box. The gas valve 102 and the water actuated member 95 connected thereto are normally kept in their seated position by means of a compression spring 108 interposed between the gas valve 32 and the opposing head of the gas valve chamber. The gas valve may be placed at any distance from the water actuated member, since the connecting stems 97 and 100 are always under tension, and may therefore be made of any length—even though of very small diameter—without danger of buckling or other distortion. An auxiliary water valve 104 is engaged by a head on the stem 97 in such a position that when the water actuated member 95 is raised to open the gas valve 102, the valve 104 will

be seated by its spring and close off the opening between the chamber 98 and the chamber 94. A small pipe 105 leads from the chamber 98 to the cold water supply pipe 5 in front of the check valve 72. An outlet 107 leads from the center of the chamber 94 to the house supply system. L' is the inlet to the gas valve chamber and N' is the outlet leading to the burners.

10 The operation of this control apparatus is as follows: When the parts are cold, the contraction of the liquid in the thermostat chamber retracts the knife edge 84 and allows the valve 89 to be lifted to the position 15 shown in the figure, thereby opening the port 93 and closing the port 92. When the flow of liquid is started—as by opening a faucet connected with the house supply pipe 107—water is withdrawn from the upper 20 part of the chamber 94, thereby decreasing the pressure on the top of the member 95, and the latter is lifted away from its seat 96 and forced against the seat 96^a by the pressure of the water flowing through the 25 port 93. The lifting of the member 95 closes the port leading to the chamber 98, thereby compelling all of the water which passes through the port 93 to flow to the discharge pipe 107. The upward movement 30 of the member 95 likewise lifts the gas valve 102 away from its seat allowing the fuel to flow from the supply pipe L' through the valve chamber to the feed pipe N' which leads to the main burners of the heater, 35 where it is ignited by the flame of an ordinary pilot light supplied through a separate pipe (not shown). When the temperature of the water flowing through the chamber 75 has been raised to a predetermined 40 point the expansion of the liquid in said thermostat will lift the arm 85 and the screw 86 out of contact with the thermostat lever 87 and the valve 89 will thereupon be depressed by the pressure of the spring 112, thus closing the opening to the port 93 and opening that to the port 92. The water 45 will now flow directly from the chamber 88 to the upper part of the chamber 94 and the valve member 95 will be pressed away from the seat 96^a and down upon its seat 96, both 50 by the pressure of the flowing water on its upper surface, and by the action of the spring 108. This seating of the member 95 allows the gas valve 102 to close and thereby cuts off the flow of fuel to the main 55 burners of the heater. The subsequent lowering of the temperature of the liquid in the thermostat chamber 75 permits the arm 85 and screw 86 to once more engage the short 60 arm of the thermostat lever 87 and the pressure of the springs 113 and 114 acting upon the arm 85 lifts the valve 89, closes the opening to the port 92 and opens that to the port 93. The flowing water will then 65 once more act upon the lower side of the

member 95 to lift it from its seat and simultaneously open the gas valve 102. When the flow of water is entirely shut off, the pressures on the two sides of the valve member 95 will be at once equalized and 70 the valve member will be returned to its seat by the pressure of the spring 108. As the valve stems 97 and 100 can in this construction be made of very small size—as they are under tension only—and as the 75 construction also permits of dispensing with a stuffing box for the stem 100, there is very little possibility of any of the valve parts sticking so as to hold the gas valve when the water has been shut off. But if such 80 sticking should occur, the valve member 95 will be forced down to its seat 96 upon the subsequent heating and expansion of the liquid in the heating receptacle in the following manner: When the flow of water 85 stops, the check valve 72 returns to its seat preventing any backward escape of the liquid to the main supply pipe, and the closing of the house service taps likewise prevents any further escape of the liquid 90 through the house supply pipe 97. If, when the flow of water is stopped, the temperature 95 is less than that at which the thermostat normally shuts off the gas, the heating of the water in the coils will first of all 100 actuate the thermostatic mechanism to open the passage to the port 92 and close that to the port 93. As the opening from the chamber 98 is also closed by the valve 107, the entire pressure produced by the further heating of the inclosed body of liquid will then be exerted on the top of the valve member 95 and will force it down to its lower seat 96. The forcing down of the valve member 95 immediately closes the gas valve 102 105 and prevents any further heating of the inclosed liquid.

When the valve 95 is in its seated position, the opening of the port between the chamber 98 and the chamber 94 establishes an 110 open circulating connection between the two ends, 73 and 74, of the heater coil and allows the contained liquid to circulate therein under the influence of the heat of the pilot light.

In Fig. 9, 121 indicates the cold water supply pipe leading to the chamber 122 in which is located the thermostatically controlled water diverting valve. As in the previous constructions, this valve has two heads 123 and 124 adapted to engage respectively with corresponding seats so as to close the openings to the ports 125 and 126 which lead into the upper and lower ends of the cylinder 127 containing the water actuated piston member 128. The piston 128 is bored at its center to receive the hollow stem 129 which passes loosely through the cap 130 and is secured water tight therein by the use of rubber gaskets 132 and 133 and a cap 134. 130

The stem 129 leads at its upper end into the upper coil of the heater and is closed at its lower end and is provided at that point with lateral ports 135 communicating with the 5 opening in the stem through a port 136 which is closed by a gravity controlled ball valve 137. The said stem 129 is further provided with a second set of ports 138 opening laterally into the upper end of the cylinder 127. The upper portion of the cylinder 127 is of reduced diameter and is bored to receive the head of a hollow plunger 139 which projects downwardly into the larger portion of the cylinder 127 and terminates in a 15 shouldered head 140 which is adapted to engage with a corresponding seat on the upper side of the water actuated piston member 128. Secured to the lower side of this piston 128 is a yoke 141 which is connected at its center to the stem 142 leading downwardly through the stuffing box 143 to the stem of the gas valve 144. This gas valve is of the same construction as that shown in Fig. 8.

The stem of the thermostatically controlled water diverting valve passes upward through a head 145 into the chamber 146 which contains a liquid thermostat 147. Said thermostat consists of two concentric corrugated tubes hermetically sealed at their 30 upper and lower ends to the heads 148 and 149, the space between the tubes being filled with some liquid having a high coefficient of expansion such as ether, alcohol, petroleum, oil, or paraffin, which is introduced 35 through an aperture 150 in the upper head. This upper head forms a part of the cap 151 which closes the upper end of the thermostat chamber 146 and on this same cap is mounted a bell crank lever 152, the short arm 40 of which is connected by a rod 153 with the lower head 149 of the thermostat, and the long arm of which carries a screw adapted to engage with the short arm of a second bell crank lever 154, which is pivoted on lugs 45 projecting from the wall of the thermostat chamber. The long arm of the bell crank lever 152 carries a stud which bears on the upper end of the stem of the water diverting valve, and is held in engagement therewith 50 by means of a spring 155. This spring 155 opposes the action of a second spring 156 placed between the lower head 124 of the water diverting valve and the cap which 55 closes the lower end of the chamber 122. The thermostat chamber 146 is provided with an inlet 157 communicating with the outlet 158 leading from the heating receptacle and with an outlet 159 communicating with the house service pipes. It is also provided with 60 a port opening 160 which leads into the upper end of the cylinder 127 at a point just above the upper end of the plunger 139 when the latter is in its highest position.

The operation of this apparatus is as follows: When the liquid in the heater is at a

temperature less than that for which the thermostat is adjusted to act, the contraction of the liquid in the thermostat chamber 147 will permit the spring 155, acting on the thermostat lever 154 to depress the water diverting valve so as to close the opening to the port 125 and open that to the port 126. When, under these conditions, a tap or faucet in the house supply system is opened, the water will be withdrawn from the heater coils, and from the hollow stem 129 communicating therewith and will also be withdrawn from the upper end of the cylinder 127 through the port openings 138 and 160. This will immediately decrease the 75 pressure on the upper side of the water actuated member 128 and the water flowing in through the supply pipe 121 and the port 126 will raise the piston 128 on the stem 129 to the position shown in dotted lines. This will open the ports 135, allowing water to flow directly from the lower end of the cylinder 127 past the ball check valve 137 into the hollow stem 129 and thence on into the heater coils. As the piston rises, it engages 80 with the lower end 140 of the plunger 139 and this also lifts this plunger against the pressure of its controlling spring 161. The lifting of the piston member 128 also closes off the port openings 138 so that in the final 85 operating position no water can flow through the port 160. As the temperature in the thermostat chamber rises, the liquid contained in the thermostat box expands, thus raising the long end of the thermostat 90 lever 154 against the pressure of the spring 155 and permitting the diverting valve 122 to be lifted by the spring 156 until the head 124 has seated itself, thus closing off the flow 95 of the cold water to the port 126 and simultaneously opening the port 125. Water will 100 then be withdrawn from the under side of the elevated piston member 128 through the ports 135, and the pressure of the inflowing water on the upper side will depress the piston member to its first position, thus closing the port 135 and opening the ports 138. Cold 105 water will now flow through the port 125 past the end of the plunger 139 and through the ports 138 to the interior of the hollow 110 stem 129 and thence on into the heater coils. In this position of the ports some cold water will also flow directly through the port 115 opening 160 into the thermostat chamber and mix with the hot water entering that 120 chamber through the inlet 157. This will serve to more quickly reduce the temperature of the water in that chamber and will increase the rapidity of action of the thermostat in restoring the water directing 125 valve to its original position, thereby again lifting the piston member 128 in the manner previously described. The rising and falling movements of the piston member 128 operates in opening and closing the gas 130

valve through the engagement of the end of the stem 142 with the end of the stem 144 thus alternately starting and stopping the flow of fuel to the main burners of the heater. When the flow of water is stopped, the parts will be returned to their normal position by the action of the springs 161 and 162, unless some sticking should occur. In such case the parts will be forced back to normal position by the continued heating and expansion of the inclosed body of water in the heater in the same manner as previously explained in connection with the description of the construction of Figs. 7 and 8. Thus on shutting off the tap in the house supply system and stopping the flow of water the ball valve 137 will automatically return to its seat, and pressure generated in the liquid in the heater coils by any continued heating of the same will be communicated through the port 160 to the upper side of the plunger 139 and will force the latter, together with the piston 128, back to its normal depressed position. When this has occurred, the port opening 160 will provide for a continued circulation of the water through the ports from the inlet to the outlet side. In order to facilitate the movement of the piston member 128 at the extremes of its travel, and in order also to prevent any movement at all when the flow of water is less than a certain amount, I provide small leakage ports 163, 163, which allow a certain small amount of liquid to pass directly from the side of the piston member to the other.

In the construction shown in Fig. 10, 171 indicates the cold water supply pipe leading into the chamber in which is located the thermostatically controlled water directing valve 172. As in previous cases, this valve is provided with two heads adapted to close the openings to the two ports 173 and 174 communicating respectively with the upper and lower ends of the cylinder 175 which contains the water actuated piston member 176. An outlet 177 leads from the upper end of the cylinder 175 to the inlet 178 of the heating coil or heating receptacle. The water actuated member 176 is bored at its lower end to receive the conical plunger 179 which is held in the head 180 by means of a spring 181 and a nut 182. The stem 183 is secured to the water actuated member 176 just above the end of the conical plug valve 179, passes down through the latter and through a stuffing box 184 in the end of the head 180 and engages by means of a fork 185 with the stem 186 of the gas valve 187. The water actuated member 176 is further provided with a valve seat 188 upon which rests the valve 189, the latter being held lightly on said seat by means of a weak spring 190 interposed between the valve 189 and the head 191 which is secured to the upper end of the piston 176. A second stem

192 which passes freely through the center of the head 191 and carries a valve 193 which is adapted to close a port opening 194 leading from the upper end of the cylinder 175 into a chamber 195, and this chamber communicates in turn through a small port opening 196 with the chamber containing a thermostat 198 which controls the position of the water directing valve 172. The inlet 178 communicates with the upper end of a heating chamber of any desired form—preferably a coil of copper pipe—and the water after passing through this receptacle emerges through a pipe 199 which enters the lower end of the thermostat chamber 197. An outlet 200 leads from the upper part of this chamber to the house supply system. The thermostat in this construction consists of a thin disk-shaped hollow chamber which is filled with liquid having a high coefficient of expansion, and preferably having considerable density and viscosity, such as heavy petroleum oil, paraffin, mercury or fusible metal which melts at a temperature less than that for which the thermostat is designed to act. This chamber is provided with a central pipe member 201 containing an accurately fitted piston or plunger 202 which projects through the lower head of the thermostat chamber and is in abutting engagement with the upper end of the stem 203 which passes down through the water directing valve 172 and terminates in a head 204 bearing upon a compression spring 205 interposed between said head and the cap 206 which closes the lower end of the chamber containing the water directing valve 172. A second compression spring 207 is interposed between the upper side of said valve 172 and the opposite end of the chamber containing said valve. The port opening 174 is provided with a ball check valve 208 which is held lightly to its seat by means of a spring 209. A heavy spring 210 is interposed between the upper side of the water actuated piston 176 and the opposing head of the piston chamber 175 and serves to hold said member 176 normally in the position shown in the figure.

The operation of this control apparatus is as follows: When the water in the apparatus is at a lower temperature than that for which the thermostat is designed to act, the head of the plunger 202 is withdrawn from engagement with the end of the stem 203 and the pressure of the spring 205—which is about twice as strong as the spring 207—lifts the stem 203 and with it the water directing valve 172 until the upper head of said valve closes the opening to the port 174. This leaves the port 173 in communication with the inlet pipe 171, and when a tap in the house service pipe 200 is opened and water is withdrawn from the heater and from the upper end of the cylinder 175

through the opening 177 and the port openings 194 and 196, the water flowing in through the port 173 lifts the piston 176 away from valve 179 and allows the water 5 to flow past this valve to the upper side of the piston member 176. This water lifts the valve 189 from its seat thereby affording a free passage way for the liquid to the inlet 178 of the heating receptacle. The lifting 10 of the piston member 176 frees the head of the stem 192 from engagement with the upper head 191 of said piston and allows the spring 211 to seat the valve 193, thus closing the port opening 194 and shutting off the 15 direct flow of water from the upper end of the cylinder to the thermostat chamber 197. The lifting of the valve member 176 brings the forked end 185 of the stem 183 into engagement with the head of the gas valve stem 186, and the continued upward movement 20 of said piston lifts the gas valve 187 from its seat, allowing fuel to flow to the gas valve chamber from the feed pipe L⁴ to the supply pipe N⁴ which communicates with 25 the main burners of the heater. The lifting of this gas valve brings a leather washer on its upper side into engagement with a boss on the inner side of the head through which stem 186 passes and thus prevents any leakage 30 of gas around that stem even though no stuffing box is used. If, while water is still flowing, the temperature of the discharged liquid reaches a point above that for which the thermostat is set (it may be set to act at 35 any temperature by means of the screw 214) the expansion of the liquid in said thermostat chamber forces out the plunger 202 until it engages with the end of the stem 203 and compresses the spring 205 sufficiently to allow 40 the water directing valve 172 to be forced down by the spring 207 until the opening to the port 173 is closed and the opening to the port 174 is opened. The inflowing water will now pass through the 45 port 174 to the upper side of the piston 176 and the pressure of this water acting in conjunction with the spring 210 will force the piston member 176 back to its first position, the cold water now flowing directly through 50 the port 174 to the opening 177 and thence on to the heating receptacle. The downward movement of the piston 176 frees the fork 185 from engagement with the head of the gas valve stem 186 and allows the gas 55 valve 187 to be seated by the pressure of its own spring, thus closing off the flow of fuel to the main burners. The downward movement of the piston 176 likewise brings its head 191 into engagement with the head 60 of the valve stem 192 and opens the port 194, thus allowing a small amount of cold water to flow directly from the upper end of the cylinder 175 through the port openings 194 and 196 into the thermostat chamber 197 where it mixes with the inflowing 65

hot water and serves to somewhat reduce its temperature so that the thermostat 198 will be rapidly cooled down to a point where it acts to release the stem 203 and permit the spring 205 to lift the water directing valve 172 to its first position in which the port opening 173 is open and the port opening 174 is closed. This once more reverses the movement of the inflowing water so that it passes to the lower end of the cylinder 175 70 lifting the piston 176, opening the gas valve 187, and permitting the closing of the valve 193 in the manner already described. This alternate reversal of the flow of cold liquid to the lower and upper sides of the water 75 actuated member 176, with the consequent lifting and depression of said member, and the consequent opening and closing of the fuel supply valve, will continue as long as the water flows through the heater and is 80 successively cooled or heated below or above the point at which the thermostatic control is set to act.

When the flowing water is completely shut off, the piston member 176 is normally 85 returned to its lowest position—if at that time it was not in that position—by the spring 210. But if for any reason the pressure of the spring 210 should be insufficient to restore the piston member 176 to its normal position—because of the “sticking” of 90 any of the parts—the construction of the apparatus is such that said piston will be forced down by the continued heating of the liquid in the heating receptacle in the 95 following manner: As soon as the flow of water stops, the valves 189 and 208 will be seated by their respective springs and thus confine the liquid in the heater between 100 these valves and the body of water in the closed house service pipe 200, and as this body of water continues to heat up, it will exert a positive pressure on the top of the piston 176 which will ultimately force that piston to the lowest position and thus insure 105 the closing of the gas valve 187 and the complete cutting off of the fuel supply to 110 the main burners.

In the lowest position of the piston 176 the port opening 194 is always open, and 115 this affords a free communication between the inlet 178 and the outlet 199 of the heating receptacle, and insures a free circulation of the liquid therein under such heating effects as may be produced at those 120 times by the action of the small pilot light.

Fig. 11 illustrates another application of the invention. In this construction, 221 is the cold water inlet leading from the main to the upper heater coil, such pipe being provided with the spring-held check valve 222 for giving a difference in pressure on the two sides thereof when the outlet from the heater is opened. 223 is a piston working in the cylinder 224 and provided with a 125 130

stem 225 for pulling the gas valve (not shown but constructed as in the other forms of invention heretofore described), open when the pressure on the two sides of the 5 piston 223 is unbalanced and the piston moves to the right. Beneath the cylinder 224 is a valve chamber 226 provided with a reciprocatory valve 227 having washers 228 and 229 adapted to seat against the 10 seats 230 and 231. The valve is also provided at its ends with the seats 232 and 233 adapted to seat against the washers 234 and 235. The valve is operated from the thermostat by means of a stem 236, the connection 15 being such that the valve is moved to the left when the temperature of the water in the heater rises above a predetermined point.

The operation, assuming the parts to be in the position shown, and the water in the 20 heater cold, is as follows. On opening the outlet from the heater, water flows into the heater through the inlet pipe 221. This flow of water causes a difference of pressure on the opposite sides of the valve 222, the pressure on the right hand side being less than that on the left hand side. This difference in pressure is communicated to the opposite sides of the piston 223, via the port 237, passage 241, chamber 226 and port 238 on 25 the one hand, and the port 239, chamber 226' and port 240 on the other hand. This differential pressure on the two sides of the piston moves it to the right, thus opening the gas valve, and permitting a free flow of 30 gas to the burners of the heater. This action will continue as long as the outlet from the heater is open and the temperature of the water in the heater is below a predetermined point for which the thermostat is 35 set. If the temperature of the water rises above such point, the thermostatic controlling means cause the movement of the stem 236 to the left. This causes the seat 232 to engage the washer 234 and to disengage the 40 seat 233 from the washer 235. At the same time the seat 230 engages the washer 228, and the washer 229 is disengaged from the washer 232. This effects a reversal of the 45 differential pressure on the two sides of the piston 223, as the right hand side of the piston is now connected with the port 237, via the passage 241, passage through the valve 227, chamber 226' and port 240, while the left hand side of the piston is connected with 50 the port 239, via the chamber 226 and port 238. This reversal of differential pressure on the piston 223 moves it to the left, thus closing the gas valve. When the outlet 55 from the heater is closed with the water cold, the piston 223 assumes the position shown in the figure, by reason of the small port 242 in the check valve which permits an equalization of pressure on opposite sides of the check valve when no water is flowing, and 60 allows said piston to be moved to the left

by the unbalanced pressure on the piston due to the stem 225 and by the action of a supplemental spring 244. When in the closed position, the opening around the stem 225 is sealed by the engagement of a washer 70 245 secured to the central boss of the piston 223, with an opposing boss 246 on the cylinder head. This prevents any leakage of liquid from the cylinder when the heater is not in operation even though the stuffing 75 box 247 may be quite loose. As the strain on the stem 225 is solely one of tension said stem may be made very small thus reducing to a minimum the frictional resistance to its movement through the stuffing box even 80 when the latter is accidentally screwed up too tightly.

The piston 223 does not have to move over any open ports, and may be therefore provided with soft packing rings 247 which effectually prevent leakage from one side of the piston to the other while offering very little resistance to movement in either direction. Finally since no water flows through the cylinder 224, and the only movement of 85 the liquid through the ports 237 and 239 is that required to provide for the differential displacement of the piston member 223, there is very little opportunity for the deposit of sediment around the working parts or for 90 corrosion of the engaging surfaces. The movement of the liquid is so small that the port openings 237 and 239 may, if desired, be filled with porous filtering plugs which will effectually prevent the entrance of any 95 dirt or grit to the valve and piston chambers, while interfering not at all with such slight movement of the liquid therein as is necessary to effect the required movements of the parts. It will also be noted that the construction of the water diverting valve and its seats is such that the entire mechanism may be readily removed and replaced by removing the cap 248, and in case of wear the 100 valve seats 234 and 235 can each be separately adjusted by screwing in or out the 105 plugs on which they are mounted.

For all these reasons the danger of the water piston "sticking" in the open position is in this construction practically eliminated 110 and no provision for forcing it back to its closed position other than the spring 244, is necessary.

Having thus described my invention and 115 illustrated its use, what I claim as new and desire to secure by Letters Patent is the following:

1. In an automatic water heater, a burner, a gas valve for controlling the supply of gas to the burner, a pair of pressure chambers, 120 means actuated by differential pressures in the chambers for operating the gas valve, thermostatic means governed by the heated water, means whereby differential water pressures are applied to the two chambers 125 130

- from the heater when the outlet from the heater is opened to secure the opening of the gas valve, and means actuated by the thermostatic means whereby the pressures in the two chambers are interchanged and the gas valve closed when the temperature of the water rises above a predetermined point.
2. In an automatic water heater, a burner, a gas valve for controlling the supply of gas to the burner, a pair of pressure chambers, means actuated by differential pressures in the chambers for operating the gas valve, communications from the chambers to separated points of the heater having different pressures when the outlet from the heater is open, thermostatic means operated by the heated water, and means actuated by the thermostatic means whereby the said communications are reversed and the pressures in the chambers reversed when the temperature of the water in the heater rises above a predetermined point.
3. In an automatic water heater, a burner, a gas valve for controlling the supply of gas to the burner, a member controlled by variations of water pressure in the heater for opening the gas valve and arranged to receive a given pressure on one side when the outlet from the heater is opened, thermostatic means governed by the heated water, and means governed thereby for securing a shift of the said given pressure to the other side of the said member, and a closure of the gas valve when the temperature of the water in the heater rises above a predetermined point.
4. In an automatic water heater, a burner, a gas valve for controlling the supply of gas to the burner, a member controlled by variations of water pressure in the heater arranged to receive a given pressure on one side to open the gas valve when the outlet from the heater is opened, thermostatic

means governed by the heated water, and a valve governed thereby and arranged to shift the said given pressure to the other side of the said member and secure a closure of the gas valve when the temperature of the water in the heater rises above a predetermined point.

5. In an automatic water heater, the combination of a water heating conduit, a fuel supply valve, a pressure motor for governing the fuel valve, said motor having a reciprocating member therein dividing said motor into two chambers, each being in communication with said conduit whereby differential water pressures are sustained in said chambers when water is being discharged from said conduit, a thermostat governed by the heated water, and means actuated by the thermostat adapted to interchange said water pressures when the heated water rises above a predetermined degree whereby the fuel supply valve is closed.

6. In a water heater, the combination of a valve casing comprising a cylinder having an outlet port communicating with the heater, a piston valve in the cylinder movable over said port, water inlet passages to the cylinder on opposite sides of said piston, a valve controlling both of said passages, a thermostat exposed to the water heated in the heater and operatively connected to the last mentioned valve, and a gas supply valve to the burner of the heater controlled by the movement of said piston.

In testimony whereof I have hereunto signed my name in the presence of the two subscribed witnesses.

FRANK L. O. WADSWORTH.
